WRENCH

Filed Oct. 1, 1930

UNITED STATES PATENT OFFICE

JOE S. MCKIBBON, OF COLUMBIA, TENNESSEE

WRENCH

Application filed October 1, 1930. Serial No. 485,714.

My invention relates to improvements in wrenches, for operating upon round work, such as pipes, rods, bolts, nuts, etc.

An important object of the invention is to provide a wrench of the above mentioned character having co-acting stationary and movable jaws, and so constructed that the movable jaw is shiftable rearwardly upon engagement with the work and tilted laterally inwardly, for binding action with such work.

A further object of the invention is to provide a wrench of the above-mentioned character, which is extremely simple in construction, cheap to manufacture, and convenient in use.

In the accompanying drawing, forming a part of this specification, and in which like numerals are employed to designate like parts throughout the same,

Figure 1 is a side elevation of a wrench embodying my invention, showing the jaws in closed position.

Figure 2 is a similar view with the jaws somewhat opened, parts being shown in central vertical longitudinal section,

Figure 3 is a similar view, with the jaws further opened and parts in central vertical longitudinal section, and Figure 4 is a perspective view of a sleeve included in an adjustable connection or turn-buckle between the jaws.

In the drawing, wherein for the purpose of illustration, is shown a preferred embodiment of my invention, the numeral 5 designates a handle, provided at its forward end with an enlarged portion 6, carrying a shank 7, preferably integral therewith, and this shank carries a stationary jaw 8. Arranged opposite the stationary jaw 8 is a movable jaw 9, carried by a movable shank 10. The jaws 8 and 9 are provided upon their inner faces with serrations 11, as shown. The enlarged portion 6 is provided upon one side of the shank 7 with a recess 12, having a curved wall 13, as shown. This recess receives the rear end of the movable shank 10, having a curved face 14. The recess 12 has a greater width than the end of the shank 10, as shown.

The shank 10 is provided, near its rear end, with a transversely inclined slot 15, which slot is longitudinally curved, as shown. The slot 15 is disposed at an angle of about 45° to the longitudinal axis of the shank 10. 55 The slot 15 receives a pin 16, rigidly attached to the side walls of the recess 12. This pin engages the rear wall of the slot 15 and thereby limits the forward movement of the shank 10, and will engage the forward end 60 wall of the slot 15, to thereby limit the rearward movement of the shank 10. The shank 10 is projected forwardly by means of a compressible coil spring 17, held within a recess 18, and the forward end of this spring 65 receives a lug 19, projecting from the rear end of the shank 10.

An adjustable connecting element or turn-buckle 20 is employed for connecting the jaws 8 and 9. This adjustable connecting element comprises bolts 21, provided at their outer ends with eyes 22. These bolts are arranged within transverse recesses, 23, formed within the jaws, and the eyes 22 receive pins or pivots 24, attached to the jaws. The 70 bolts 21 receive thereon a rotatable sleeve 24', having screw-threaded engagement therewith, the threads of the bolts being positively pitched. The sleeve is provided with a milled head 25, arranged centrally thereof, and this 75 milled head is disposed adjacent to recesses or depressions 26, so that it may be conveniently engaged with the thumb or fingers, to turn the same.

The operation of the wrench is as follows: 85 The sleeve 24' is turned to move the jaw 9 from the stationary jaw 8, for a considerable distance, depending upon the size of the work, such as a pipe. The jaws are then applied to the opposite sides of the work, and when the 90 handle 5 is swung downwardly to turn the work, the pressure shifts the movable shank 10 longitudinally and rearwardly with relation to the shank 7, but, at the same time, the pin 16 being arranged within the slot 15, 95 will shift the rear end of the shank 10 outwardly, causing the movable jaw 9 to be swung inwardly, for binding action with the work. The reverse of this action occurs when 100 the handle 5 is swung in the opposite direc-

tion, for taking a new hold on the work, the shank 10 being projected forwardly by the spring 17, when the pressure is released therefrom.

6 Particular attention is called to the fact that the outward end inward swinging movement of the rear end of the shank 10 is effected by the simple construction, including the pin 16 and slot 15, these parts also serving to limit the rear and forward longitudinal movements of the shank 10.

It is to be understood that the form of my invention herewith shown and described, is to be taken as a preferred example of the same, and that various changes in shape, size and arrangement of parts may be resorted to without departing from the spirit of my invention, or the scope of the subjoined claims.

Having thus described my invention, I claim:

1. A wrench comprising a handle having a stationary shank and a stationary jaw carried by said shank, a longitudinally movable shank carrying movable jaw arranged opposite the stationary jaw, said movable shank being provided near its rear end with a transversely inclined slot, a pin secured to the handle and operating within the transversely inclined slot, and an adjustable coupling arranged in advance of the slot and pin and having pivotal connections with both jaws for shifting the movable jaw laterally with relation to the stationary jaw, the arrangement of the transversely inclined slot and pin and adjustable coupling being such that the rear end of the movable shank is automatically shifted laterally and outwardly upon the rearward longitudinal movement of the movable shank.

40 2. A wrench comprising a handle having a stationary shank and a stationary jaw carried by said shank, a longitudinally movable shank carrying a movable jaw arranged opposite the stationary jaw, said shank being provided near its rear end with a transversely inclined slot, a pin secured to the handle and operating with the transversely inclined slot, an adjustable coupling arranged in advance of the inclined slot and pin and having pivotal connections with both jaws for shifting the movable jaw laterally with relation to the stationary jaw, the arrangement of the transversely inclined slot and pin and coupling being such that the rear end of the movable shank is automatically shifted laterally and outwardly upon the rearward longitudinal movement of the movable shank, and a spring tending to shift the movable shank forwardly.

45 3. A wrench comprising a handle having a stationary shank and a stationary jaw carried by said shank, a longitudinally movable shank carrying a jaw arranged opposite the stationary jaw, said movable shank being provided near its rear end with a slot dis-

posed at an angle with relation to the longitudinal axis of the movable shank, a pin secured to the handle and operating within said slot, and an adjustable coupling arranged in advance of the slot and pin and pivotally connected with both jaws for shifting the movable shank laterally with relation to the stationary jaw, the arrangement of the slot and pin and coupling permitting the rear end of the movable shank to be automatically shifted laterally and outwardly upon the rearward longitudinal movement of the movable shank.

4. A wrench comprising a handle provided at its forward end with an enlarged portion carrying a stationary shank and a stationary jaw carried by such shank, the enlarged portion of the handle also having a recess therein, a longitudinally movable shank having its inner end disposed in said recess and at its outer end carrying a jaw arranged for disposition opposite the stationary jaw, the inner end of the movable shank having an inclined slot, a pin passing through the slot of the movable shank and having connection with the handle whereby to effect a pivotal connection of the movable shank with the handle, means for coupling the movable shank and its jaw to the fixed shank so as to be movable longitudinally and laterally with relation to the stationary shank and its jaw, the arrangement of the said slot and pin being such that the rear end of the movable shank is automatically shifted laterally and outwardly upon the rearward longitudinal movement of the movable shank.

5. A wrench comprising a handle provided at its forward end with an enlarged portion carrying a stationary shank and a stationary jaw carried by such shank, the enlarged portion of the handle also having a recess therein, a longitudinally movable shank having its inner end disposed in said recess and at its outer end carrying a jaw arranged for disposition opposite the stationary jaw, the inner end of the movable shank having an inclined slot, a pin passing through the slot of the movable shank and having connection with the handle whereby to effect a pivotal connection of the movable shank with the handle, adjustable means for coupling the movable shank and its jaw to the fixed shank so as to be movable longitudinally and laterally with relation to the stationary shank and its jaw, the arrangement of the said slot and pin being such that the rear end of the movable shank is automatically shifted laterally and outwardly upon the rearward longitudinal movement of the movable shank, and a spring located in said recess and having engagement with the inner end of said movable shank to normally shift the movable shank forwardly.

6. A wrench comprising a handle having

a stationary shank and a stationary jaw carried by said shank, said stationary shank having a recess formed therein, a longitudinally movable shank carrying a movable 5 jaw arranged opposite the stationary jaw, said movable shank being provided near its forward end with a recess and being provided near its rear end with a transversely inclined slot, a pin secured to the handle and 10 operating within the transversely inclined slot, bolts extending into the recesses of the shanks and having eyes disposed within said recesses, pins carried by the shanks and pivotally mounted within said eyes, and a rotatable 15 sleeve having screw-threaded engagement with said bolts, said bolts and sleeve being arranged in advance of the inclined slot and pin and said bolts having pivotal connections with both shanks.

20 In testimony whereof I affix my signature.
